UNITED STATES PATENT OFFICE.

THOMAS F. SOMERS, OF NEW YORK, N. Y.

DESIGN FOR A BUNDLE-CARRIER.

SPECIFICATION forming part of Design No. 24,291, dated May 7, 1895.

Application filed March 29, 1895. Serial No. 543,755. Term of patent 14 years.

To all whom it may concern:

Be it known that I, THOMAS F. SOMERS, a citizen of the United States, residing in the city, county, and State of New York, have 5 invented and produced a new and original Design for a Bundle Handle or Carrier, of which the following is a specification.

My invention comprises a new design for a bundle-handle or carrier, the essential features of which consist of a stem or body portion having laterally projecting curved portions.

In the accompanying drawing an embodiment of my new design is represented in perspective.

The body portion A, comprises a loop having substantially parallel sides, joined at their lower ends, with an opening between the side portions of the loop, while the upper end of 15 the body portion is extended in laterally

curved loops B. At or near the point where the body portion is extended to form the loops, one of the loops on each side is bent inward to form a curved projection C, the curved projections on the opposite sides of the loop 25 overlapping, as shown.

The essential feature of my design comprises the looped body portion, having laterally extended curved portions.

What I claim is—

1. The design for a bundle carrier, substantially as shown and described.

2. In testimony whereof I have signed my name to this specification in the presence of two subscribing witnesses.

THOMAS F. SOMERS.

Witnesses:

GEORGE A. ST. JOHN,

KARL L. KRANCHER.
